UNITED STATES PATENT OFFICE.

CARL WINKLER, OF BERNE, SWITZERLAND.

PRINTING-MACHINE HAVING OSCILLATING PRINTING-CYLINDERS.

1,319,198.

Specification of Letters Patent.

Patented Oct. 21, 1919.

Application filed October 1, 1915. Serial No. 53,664.

To all whom it may concern:

Be it known that I, CARL WINKLER, a citizen of the Swiss Republic, residing at Berne, in the Swiss Republic, have invented 5 new and useful Improvements in Printing-Machines Having Oscillating Printing-Cylinders, of which the following is a specification.

My present invention relates to improvements in printing machines in which the impression cylinder is oscillated backward and forward over a reciprocating carriage carrying the form. Printing machines of this kind are so improved by my present invention that an exact register is rendered possible in placing the sheets into the machine, further, smearing of the freshly printed sheets is avoided, and a reliable conveyance of the sheets is assured.

20 In the drawing a printing machine constructed according to the invention is shown by way of example,

Figure 1 being a side elevation showing the principal parts of said machine.

25 Fig. 2 is a diagram representing the impression cylinder and type carriage in the position in which the grippers have just taken hold of a sheet.

Fig. 3 represents the impression cylinder 30 in section on a larger scale in order to better show the mechanism for operating the grippers.

Figs. 4, 5 and 6 are sections through the impression cylinder showing a special construction of the gripper mechanism in three different positions.

Figs. 7, 8 and 9 show the impression cylinder in different positions in regard to the mechanism for leading the printed sheets 40 out of the machine.

Figs. 10, 11 and 12 are sections of the impression cylinder representing the belts for guiding the sheets in three different positions.

45 In Fig. 1 the crank pin a is at a dead point. As a consequence the carriage b , which is driven by the toothed wheel a' at the end of the connecting rod a^2 engaging in the toothed racks b' , b^2 , is at the end of 50 its stroke and the impression cylinder c is about to change its direction of rotation. The gripping edge of the cylinder is then underneath the feed table e , the grippers f are opened by the lever g and project over 55 the edge of the table e and sheet h placed on

said table. As soon as the cylinder c begins to rotate in the opposite direction represented in Figs. 1 and 2 by an arrow the grippers f close gradually, and they are completely closed when the impression cylinder arrives 60 in the position shown in Fig. 2, so that the sheet is pulled off the table e and is wound on the cylinder c . It will be clear from Fig. 2 that the angular velocity of the cylinder c at the moment in which the grippers f 65 close and take up a sheet is very low, because the crank pin a has only advanced through one twelfth of its stroke. According as the crank pin moves in the direction of the arrow the angular velocity of the impression 70 cylinder will naturally increase, and it is greatest at the point in which the connecting rod and crank arm are at an angle of 90° .

In Fig. 3 the gripper mechanism is shown on a larger scale. This mechanism operates 75 as follows:

The sheet to be printed is placed on the feed table e against the stops i . The tongues m attached to the edge of the feed table e extend down to the stops i , so that 80 the sheet h is well supported and can be placed accurately against the stops. The impression cylinder, which is rotating backward at the time, comes to rest or changes its direction of rotation when its edge d is 85 underneath the edge m of the feed table e . During the backward rotation of the cylinder the roll k carried by an arm fixed on the shaft carrying the grippers f , runs over the block g' on the lever g , so that the grippers 90 f are opened and come to rest over the sheet h . When now the cylinder begins to turn forward the lever g is caused to move toward the axis c' of the cylinder c , so that the grippers f close slowly and take hold of 95 the sheet h . As soon as the grippers are closed the stops i rise and the sheet can then pass underneath same.

By the described construction a uniformly good application of the sheets to the cylinder c is assured. Similar machines have the drawback that owing to the weight of the type carriage and impression cylinder a certain amount of play is caused to be formed in the separate parts, so that the change in 100 the direction of motion of the cylinder takes place unevenly and consequently an exact register cannot be obtained. This unevenness is quite particularly noticeable when the impression is carried out at different 105 110

speeds. As will be clear from the above explanation these drawbacks are overcome by the sheets not being taken up by the impression cylinder at the point of change in the 5 direction of motion of the impression cylinder, but always after the forward motion of the cylinder has just begun and said cylinder has therefore still but a low speed.

In the construction of the gripper mechanism shown in Figs. 4 to 6 the points of 10 the grippers move backward over the edge of the sheet *h* in such a manner that they together with their axis—form an acute angle with the sheet. Fig. 4 shows the impression cylinder *c* approaching the end of 15 its backward stroke. The lever *g* is so moved by the crank shaft that the roll *f*³ at the end of the lever *f*² is raised by the block *g*'. Consequently the grippers *f* are 20 opened against the tension of the springs *f*⁴, so that they can then move backward over the edge of the sheet *h* placed on the feed table *e*. Fig. 5 shows the impression cylinder after it has approached somewhat far- 25 ther toward the end of its backward stroke. The grippers *f*, owing to the motion of the lever *g*, then begin to close under the tension of the spring *f*⁴. In the position shown in Fig. 6 the impression cylinder *c* 30 has moved up to the end of its backward stroke and has turned forward to such an extent that the grippers have just closed. Immediately before closing the points of the grippers slide on the edge of the sheet 35 and thus stretch and smooth the sheet *h*.

The device for delivering the printed sheets out of the machine shown in Figs. 7 to 9 has the object to so utilize the return motion of the impression cylinder that the 40 sheets are carried out with the printed surface uppermost. Fig. 7 shows the position of the cylinder after the sheet has been printed. In this position the cylinder *c* is raised from the carriage *b*, in order to prevent the printed sheet from coming into contact with the form. During the return motion of the cylinder *c* the grippers *f* remain closed and the sheet is held fast on the cylinder *c* by the belts *h*', the back edge 45 of the sheet being thus led over the tongues *n*' which previously had been raised in the position shown in Fig. 7 to allow the sheet to pass to print, but in the position illustrated in Fig. 8 they press against the cylinder *c* and thus lift the sheet and lead it toward the delivery device *n*. In the position of the parts shown in Fig. 9 the cylinder *c* has rotated back to its full extent and begins to change its direction of rotation. 50 A sheet has been delivered to the device *n* and the grippers *f* are opened again for taking up a new sheet placed on the feed table *e*.

The delivery device is driven by a spur- 65 wheel *c*⁵ attached to the impression cylinder

c, and in the driving gear *n*⁴, *n*⁵ a so-called free wheel *n*⁶ is provided, in order to cause the belts *n* to be driven in one direction only by the reciprocating cylinder *c* and at a speed corresponding to that of said cylinder. 70 The tongues *n*' are raised and lowered by the lever *n*² and rod *n*³, which latter is operated from the main shaft of the machine.

The device for guiding the sheet is shown in Figs. 10 to 12 in different positions. 75 Said device consists of belts *h*', which are connected at one end to the impression cylinder at *c*' and at the other end to rolls *o* which have the tendency to wind up like the tape of a spring measure, so that the belts 80 *h*' are always kept in a stretched condition. Fig. 10 shows the impression cylinder *c* together with a sheet *h* to be printed after the cylinder has described quarter of a revolution, the belts *h*' being unwound from the 85 rolls *o* to a corresponding extent. Fig. 11 shows the printing cylinder *c* after the impression has been effected. The belts *h*' surround the impression cylinder *c* and overlap up to the point *c*' at which they are 90 fastened and hold the sheet fast. According to Fig. 12 the impression cylinder *c* has rotated backward sufficiently to deliver the sheet to the conveying out device, the belts 95 *h*' being again wound up on the rolls *o*, so that the printed sheet is free. This sheet is leaving the impression cylinder and a new sheet is taken up by the grippers *f*.

As shown in Figs. 1, 7 and 9 the impression cylinder is raised when rotated backward, so that it does not come into contact with the carriage. For the purpose of raising the impression cylinder the following device is used:—

The axis *c*' of the impression cylinder *c* 105 is journaled in the sleeve *c*² in the side frame *c*³ of the machine. The sleeve *c*² is connected with the shaft *c*⁴ by means of the levers *p*, *p*' and connecting rod *q*. Said shaft *c*⁴ is moved in accordance with the reciprocating 110 movement of the carriage by means of the lever *p*², rod *q*', lever *r*, and eccentric *s*, so that the impression cylinder is raised at the proper moment.

What I claim and desire to secure by Letters Patent of the United States is:—

1. The described printing machine, comprising in combination, as oscillating cylinder, a carriage adapted to reciprocate backward and forward in proximity to said oscillating cylinder, a feed table to carry the sheets to be fed to said cylinder, stops for the front edge of the sheet placed on said feed table, gripping devices attached to said cylinder at such a point that during the 120 backward oscillation of said cylinder they will pass well behind said stops and of such a shape that a line connecting their points with their axis of rotation forms an acute angle with said feed table when said cylin- 125 130

- der begins its forward oscillation, and mechanism to close said gripping devices during the forward oscillation of said cylinder after the play in the driving gear of said cylinder 5 has been taken up and said cylinder is already well in its forward oscillation and the gripping devices have exerted a smoothing out action on the edge of the sheet placed on said feed table, substantially as set forth.
- 10 2. In a printing machine, the combination of an oscillating cylinder, a carriage adapted to reciprocate in proximity to the cylinder, sheet gripping devices carried by the cylinder, and means for operating the gripping devices so that they will be moved into engagement with the sheet without gripping the same just before the cylinder reaches its rearward stroke and moved into gripping 15 engagement with said sheets after the cylinder reaches its forward stroke.
- 20
3. In a printing machine the combination with an oscillating sheet carrying cylinder, of belts attached to said oscillating cylinder at one end and to automatic spring winding rolls at the opposite ends, adapted to keep said belts stretched in all angular positions of said cylinder, substantially as, and for the purpose set forth.

In testimony whereof I have signed my name to this specification in the presence of two subscribing witnesses.

CARL WINKLER.
